N. N. HILL

TOY DESK TELEPHONE

Filed July 21, 1922

UNITED STATES PATENT OFFICE.

NORMAN N. HILL, OF EAST HAMPTON, CONNECTICUT, ASSIGNOR TO THE N. N. HILL
BRASS CO., OF EAST HAMPTON, CONNECTICUT, A CORPORATION.

TOY DESK TELEPHONE.

Application filed July 21, 1922. Serial No. 576,649.

To all whom it may concern:

Be it known that I, NORMAN N. HILL, a citizen of the United States, residing at East Hampton, in the county of Middlesex 5 and State of Connecticut, have invented a new and useful Improvement in Toy Desk Telephones; and I do hereby declare the following, when taken in connection with the accompanying drawings and the characters of reference marked thereon, to be a full, clear, and exact description of the same, and which said drawings constitute part of this application and represent, in—

Fig. 1 a view in side elevation of a toy 15 desk-telephone constructed in accordance with my invention.

Fig. 2 a view thereof in rear elevation.

Fig. 3 a view thereof in transverse section on the broken line 3—3 of Fig. 1. 20 Fig. 4 an enlarged view in elevation of the bell-mechanism with the gong removed and the standard broken away.

My invention relates to an improved toy desk-telephone, the object being to provide, 25 at a low cost for manufacture, a simple, durable and pleasing toy constructed with particular reference to enabling the child using it to easily ring the bell while holding the transmitter-portion of the toy in one 30 hand, and the receiver thereof in the other hand.

With these ends in view, my invention consists in a toy desk-telephone characterized by having a bell-operating lever positioned to be included within the hand 35 grasping the standard, so as to be operated by a gripping and relaxing action of the hand, while the same retains its hold upon the standard.

My invention further consists in a toy 40 desk-telephone having certain details of construction and combinations of parts as will be hereinafter described and particularly pointed out in the claims.

In carrying out my invention, as herein 45 shown, I employ a dummy transmitter 5 facing forwardly and pivotally mounted upon a post 6 rising from a cap 7 applied to the upper end of a standard 8 furnished 50 with a circular base 9 to which is attached a braided cord 10 running to a dummy receiver 11 normally suspended in a dummy receiver-hook 12 rigidly secured by a screw 13 to the left-hand side of a band or clip 14 clamped upon the said standard. The ends

of the said band are rearwardly extended to form parallel clamping lugs 15 receiving a clamping-screw 16 upon which I pivotally mount a depending, bell-operating lever 17 located between the said lugs, which prevent 60 its sidewise movement, and arranged vertically and substantially parallel with the said standard, though, by preference, the lever will normally stand with a slight outward rake with respect to the face thereof. 65

The said lever is thus positioned directly back of and adjacent to the rear face of the standard and in line therewith, and is, therefore, included naturally and as a matter of course within the hand grasping the stand- 70 ard and, consequently, falls easily and completely under the control of the hand, as the same is contracted and relaxed, no special reaching effort of the fingers being required to operate it. To permit the lever 75 to be so grasped and operated, it is extended below the bell, which is located in front of the standard, as will presently be described.

The said screw 16 also mounts a bell-actuator made, as shown, of a single piece 80 of wire and comprising a coil 18 through which the screw passes, a depending arm 19 lying within and engaged by the lever 17 and a horizontal arm 20 extending from rear to front through a clearance-passage 85 21 formed transversely in the standard 8 and also through a vertical clearance-slot 22 in the back of a cup-like bell-housing 23 rigidly secured to the front of the band or clip 14, and, therefore, at a point opposite 90 the lugs 15 thereof, and virtually under the dummy transmitter 5. The extreme end of the said arm 20 enters a hole 24 in the arm 25 of the rack 26 of the bell-mechanism proper, the said arm 25 being hung upon a 95 stud 27 in the bell-housing 23. As shown, the rack 26 meshes into a pinion 28, turning on a stud 29 and carrying a wheel 30 meshing into a pinion 31 turning on a stud 32 and mounting a two-armed striker-carrier 100 33 furnished at its ends with loose strikers 34 which, when thrown outward, hit the gong 36 for the sounding of the bell. A spring 37, attached to the arm 25 and to the housing 23, as shown in Fig. 4, normally 105 holds the rack 26 in its depressed position and the bell-operating lever 19 in its normal position, or at the limit of its outward movement away from the standard, the lever being stopped in this position by the engage- 110

ment of the guard 38 at its upper end with the rear face of the standard.

As thus constructed and arranged, the bell is located under the transmitter and faces full front, while the bell-actuating lever is located back of the standard and out of sight. The resulting effect is much more pleasing than when the bell is located at the left of the standard, opposite the receiver-hook, and is seen edgewise, rather than in front. When the child, with its right hand, grasps both the standard 8 and the lever 19 within the right hand at the same time and exerts pressure upon the latter by closing the hand, the tension of the spring 37 is overcome and the lever 25 is lifted, with the effect of causing the rack 26 to set the bell-mechanism in operation for rotating the striker-carrier 33 and so sounding the bell. The instant that pressure upon the lever 19 is relaxed by somewhat unclosing the hand, the spring 37 exerts itself to restore the parts to the normal position, during which action the bell is again sounded. The child, meanwhile, may be supposed to be holding the receiver to the ear with one hand, while grasping the standard and easily operating the bell with the other hand, by naturally closing and unclosing the same, which cannot be done in toy desk-telephones in which the receiver-hook must be operated or "jiggle" for ringing the bell.

I would have it understood that I do not limit myself to the exact construction shown herein and described, as the various features of the toy may be modified, both in form and construction, without departing from my present invention, which is characterized by the use of a bell-operating lever positioned to be included within the hand grasping the standard, so as to be operated by a closing and unclosing action of the hand while the same retains its grip upon the standard.

I claim:

1. In a toy desk-telephone, the combination with a base, of a standard rising therefrom, a transmitter surmounting the standard, a receiver connected by a cord with the toy, a bell offsetting from the upper portion of the standard, an operating-lever arranged in substantial alignment with the said standard and pivotally connected at its upper end therewith at a point opposite the said bell,

and a bell-actuator extending transversely through the standard and connecting the said bell and lever, whereby the bell is operated by a closing and unclosing action of the hand upon the said lever, while the same retains its grasp upon the standard. 55

2. In a toy desk-telephone, the combination with a base, of a standard rising therefrom, a transmitter surmounting the standard, a receiver connected by a cord with the toy, a bell offsetting from the upper portion of the standard at a point under the transmitter in the normal position thereof, a receiver-hook applied to the standard and extending outward therefrom in a line at a right angle to the axis of the bell, an operating-lever arranged in substantial alignment 70 with the said standard and pivotally connected at its upper end therewith at a point opposite the said bell, and a bell-actuator extending transversely through the standard and connecting the bell with the said operating-lever, which is operated by a closing and unclosing action of the hand, while the same retains its grasp upon the standard. 75

3. In a toy desk-telephone, the combination with a base, of a standard rising therefrom, a transmitter surmounting the standard, a receiver connected by a cord with the toy, a clamp mounted upon the upper portion of the standard, a bell applied to the said clamp at a point under the transmitter 80 in the normal position thereof, a receiver-hook rigidly connected with the said clamp and extending horizontally outward from the standard in a line at a right angle to the axis of the bell, an operating lever 85 pivotally mounted in the said clamp in close proximity to the standard with which it is substantially aligned, and a bell-actuator extending transversely through the standard and connecting the bell with the said lever, 90 which is operated by a closing and unclosing of the hand, while the same retains its grasp upon the standard. 95

In testimony whereof, I have signed this specification in the presence of two subscribing witnesses. 100

NORMAN N. HILL.
